L. M. HAWES.
AUTOMATIC GATE.

No. 597,237.

Patented Jan. 11, 1898.

UNITED STATES PATENT OFFICE.

LEVI M. HAWES, OF SACRAMENTO, CALIFORNIA.

AUTOMATIC GATE.

SPECIFICATION forming part of Letters Patent No. 597,237, dated January 11, 1898.

Application filed August 17, 1897. Serial No. 648,486. (No model.)

To all whom it may concern:-

Be it known that I, LEVI M. HAWES, a citizen of the United States, residing at Sacramento, county of Sacramento, State of California, have invented an Improvement in Automatic Gates; and I hereby declare the following to be a full, clear, and exact description of the same.

My invention relates to improvements in that class of gates which are adapted to be opened and closed by the approaching and receding vehicle.

It consists in details of construction which will be more fully explained by reference to the accompanying drawings, in which—

Figure 1 is a plan view of my gate and its connections. Fig. 2 is an end view of the plate Q and its adjuncts. Fig. 3 is an elevation of a portion of the gate. Figs. 4, 5, 6, 7, 20 and 8 are details to be hereinafter referred to. Fig. 9 is a top view of the lower hinge, showing its working.

This gate may be made either double or single. If made single, a single fixed post A carries the attachments from which the inner gate-stile B is hung, so that it swings about the connections to open or close, and the outer end closes and latches against the fixed post.

In the present case I have shown my device as applied to a double gate, in which there will be two of the fixed posts A upon opposite sides of the roadway and two gates having the swinging or hinge-carrying stiles B connected with the posts A, while the meeting ends of the gates are adapted to latch together by means of stiles C, which meet centrally, one of said stiles having projecting latches D fixed at top and bottom, respectively, and the other carrying the notched latch-plates E, with which the latches D engage. The peculiarity in these attachments, which are shown in detail in Figs. 4 and 5, is the formation of the parts D and E with plates from which they project and which are attached to the respective posts by bolts, while each of the plates E has an inwardly-projecting plate, as at e, which is mortised into the wood of the stile, so as to form a strong brace and prevent the plates from being loosened or broken from the gate by the constant concussion caused by their latching when closed

together. The plate from which the catch D projects is vertically slotted, so that it may be moved up or down to adjust it to the slotted catch-plate E.

By having latches at both top and bottom the gate will be firmly held when latched, and cannot be warped or twisted by pressure either above or below, as in the case of a single latch.

The framework of the gate is preferably made of light timbers suitably joined together, and may be covered with a wire network or screen, which will effectually prevent the passage of small animals.

Upon the post A, at the upper end, is fixed a bracket G, projecting from the face of the post adjacent to the inner gate-stile B, and H is a rod bent so that the upper end passes vertically through a hole in the outer end of the bracket G, while the lower portion is bent inwardly and has an eye at the lower end, which is firmly bolted and secured to the post A, as shown.

The protruding bracket G forms a strong brace for the pin H and holds the latter at a sufficient distance away from the post A without danger of its becoming loose by the wrench or strain of the swinging gate.

Upon the stile B is fixed a socket-piece I, which has an interiorly-projecting plate i, mortised into the post A, where it is secured by bolts passing through it, so as to prevent it from being loosened or removed.

At the bottom of the post A is a fixed permanent plate or support J, and upon this is pivoted a flat segmental plate K, which lies horizontally upon the support J and has an upwardly-projecting peripheral rim K'. (See Fig. 7.) Upon the opposite side and in a smaller arc of a circle surrounding the pivot-pin k is a segmental toothed portion k². The pivot-pin k passes down through the supporting-plate J and has fixed to its lower end a bar l, which projects each way from the pin, for a purpose to be hereinafter described.

The bottom of the stile B has fitted to it a concaved toothed segment M, the teeth of which are adapted to engage with the teeth k² of the segment K upon the post. This segment M has an upwardly-projecting plate m, (see Fig. 6,) extending along up the inner face of the post B, into which it is sunk, a

horizontally-projecting plate let into the bottom of the stile, and a diagonally-connecting web mortised into the stile, the whole being bolted firmly in place, so as to secure the parts 5 to prevent their becoming loosened from the stile, this being an important feature of all these attachments, because the alternate wetting and drying of the wood and the movements of the gates soon loosen such attachments and destroy the usefulness of the gate.

The object of the toothed segments k^2 and M is to move the bottom of the gate outwardly and cause it to swing, the top remaining essentially in place upon the hinge-pin H, so 15 that the first movement caused by the turning of the segment K engages one end with the corresponding end of the segment M, thus pushing the bottom of the gate outwardly from the post A and lifting the end where the latches D and E engage until they are clear 20 of each other, or in case of a single gate the latch D will be clear of the notched catch E of the fixed post. The gate is thus lifted and the bottom support or hinge is shifted by reason 25 of one of the edges M^2 of the segment M resting in the corresponding socket k^3 of the segment K, and as this socket is at one side of the pivot-pin k it will be seen that the gate thus having its hinge-pins thrown out of line its tendency will be to swing in the direction opposite to the point of temporary support.

The manner in which this gate is moved is by means of wheel-plates N, located in the 35 roadway. These plates are supported upon curved staples O, which pass through and allow the plates to swing easily from side to side. Each plate is retained in its vertical position by springs, as shown at P, which 40 press against it, but will yield to allow it to lie down flat in either direction. Fixed to one side of this normally vertical plate N is a projecting plate Q, having upon it a pin Q' for the attachment of a cord or chain, and it 45 also has a pressure-pin near the outer end, as shown at Q^2 , under which the cord or chain R passes, so that when the plate N is tilted in either direction the action of the plate Q is that of a lever pulling upon the cord R. 50 By means of a fixed pulley R', over which the cord passes, the movement of the cord is increased when the plate Q is turned, as above described.

When the plate N is tilted in one direction, 55 the projecting lever-plate Q will be pressed downward, and I have shown an excavation or chamber made beneath it to allow this plate to drop into the excavation when the plate N is forced into a flat position by the 60 wheel of a carriage passing over it from the right, as shown in the drawings; but when the wheel passes over it from the opposite direction, or from the left, it will be seen that the plate Q will be thrown upward when the plate 65 N lies flat and will pull the cord in the same manner. The cord R from the plate Q passes around the vertical flange K' of the segment

K, and there being one of the plates N placed in the roadway or approach to the gate on either side thereof it will be seen that when 70 the carriage passes over the plate from either side it will act to pull the cord R, which, passing around the segmental flange K', rotates the segment K about its pivot-pin k . This presses the indentation or socket k^3 against the 75 outer end M^2 of the segment M upon the gate-stile B, which, as before described, forces the bottom of the gate-stile outward, thus lifting the outer end and disengaging the latch. At the same time the support for the gate-stile 80 is temporarily transferred to the point M^2 , which is in contact with the socket k^3 , and the gate being thus tilted or upon an axial line which is not perpendicular will have a tendency to swing about this temporary axial 85 line, thus opening itself and swinging back against the stop-post, of which there is one upon the side of the roadway in line with the main post A, as shown at A^2 . A catch a is fixed to each of these posts and adapted to 90 engage with the latches D upon the gate-stile C, so as to retain the gate in its open position until a carriage passes over the opposite plate N, when the segment K will be moved in the opposite direction, which will again 95 disengage and tilt the gate, so that it will close.

In order to operate the two gates simultaneously, I have shown the transverse bars l passing through the bottom of the pivot-pin 100 k of the segment K and turnable with the segment and pin. These bars or rods l have their ends connected in a channel beneath the gates, so that the cords cross each other centrally beneath the gates, the cord from one end of 105 one of the arms l connecting with the opposite end of the other arm l, as shown in plan view. By this connection both gates are operated from the single turning plate N, because when this plate is operated and turns at segment 110 K the pin or rod l of the pivot-pin will be turned with it, and, pulling through its connecting wire or cord upon the end of the opposite pin l, the segment K of the other gate will be simultaneously turned, so that both 115 gates will be unlatched and caused to swing open at the same instant.

The operating parts of the gate being at the bottom instead of the top are more permanent by being close to or below the surface of the ground and are not liable to be moved out of place by the springing or twisting of the upper ends of the posts.

Having thus described my invention, what I claim as new, and desire to secure by Letters 125 Patent, is—

1. In a gate, a fixed post to which the gate is hinged, upper hinge-pins fastened at the bottom bent diagonally and with supporting bracket-braces, corresponding eyes let into 130 and fixed to the top of the inner ends of the gate, concaved segments fixed to the lower ends of the inner gate-stiles and corresponding segments pivoted to the bottom of the fixed

posts having sockets upon each side of their pivot-point adapted to engage the ends of the gate-stile segments whereby the gate is retained in a closed position when the turnable segments are in their normal position and is tilted so as to swing when said segments are turned to an angle.

2. In a gate, a fixed post having an upper stationary hinge connection, a segment turnable about a pivot-pin at the base of said post having a reversely-curved toothed segment of smaller diameter, a concaved toothed segment fixed to the bottom of the gate-stile adapted to engage with the turnable segment, 15 a flange projecting upwardly from the turnable segment, wires or cords passing around said flange from opposite directions connecting with wheel-plates fixed in the roadway whereby the depression of said wheel-plates 20 acts to turn the segments, unlatch the gate and throw the axis out of a vertical line.

3. In a gate, a fixed post having a hinge connection at the top upon which the inner gate-stile is turnable, a segment pivoted at 25 the bottom having a vertical flange around its periphery and contact-points upon each side of the pivot-pin within the ends of the segment, a concaved segment fixed to the bottom of the inner gate-stile, the ends of which 30 contact with the points upon the movable segment when the latter is in its normal position, one of said ends being forced outwardly when the segment is turned and at the same time forming a temporary inclined axial line with 35 the upper hinge about which the gate is turnable.

4. In a gate, a fixed post having a hinge at the top about which the inner gate-stile is turnable, a turnable segment pivoted at the 40 bottom, engaging a corresponding concaved segment fixed to the bottom of the gate-stile

and having an upwardly-projecting segmental flange, wires or ropes having their ends fixed at the ends of the segmental flange and passing in opposite directions around said flange, 45 spring-pressed wheel-plates held vertically in the roadway, each having a plate projecting at right angles and turnable therewith and having an attachment for the opposite end of the wire or rope which passes around the segment whereby the depression of the plate acts to turn the segment about its vertical pivot and change the axial hinge-line of the gate. 50

5. In a gate, fixed posts A upon opposite sides of the roadway, double gates meeting 55 in the center having engaging latches, the stiles of said gates adjacent to the fixed posts having permanent hinges at the upper ends, and concave segments at the lower ends, turnable segments fixed at the base of each of the 60 posts A and engaging the ends of the gate-stile segments, pivot-pins fixed to said turnable segments, passing through supports within which they are turnable, transverse arms extending through the lower ends of said pivot- 65 pins, those upon opposite sides being connected together by wires or ropes crossing each other as shown, spring-pressed wheel-plates standing normally in a vertical position in the roadway having projecting plates, 70 wires or ropes extending from said projecting plates to the turnable segments at the bases of the fixed posts whereby the depression of the wheel-plates turns the segments, unlatches the gates and acts to operate both gates si- 75 multaneously.

In witness whereof I have hereunto set my hand.

LEVI M. HAWES.
